UNITED STATES PATENT OFFICE.

JOHN S. CHAMBERS, OF NEW YORK, N. Y., ASSIGNOR TO CHAMBERS VALVE COMPANY,
OF NEW YORK, N. Y., A CORPORATION OF NEW YORK.

SUPERHEATER-HEADER.

1,209,117.

Specification of Letters Patent. Patented Dec. 19, 1916.

Application filed September 10, 1915. Serial No. 49,931.

To all whom it may concern:

Be it known that I, JOHN S. CHAMBERS, a citizen of the United States, residing at New York, in the county of New York and 5 State of New York, have invented certain new and useful Improvements in Superheater-Headers, of which the following is a specification.

This invention relates to superheaters and 10 more particularly to superheaters applicable to boilers of the locomotive type.

One of the objects of the present invention is to provide a simple and practical superheater header adapted to prevent burning 15 out of the superheater tubes.

Another object is to provide a superheater header especially adaptable to boilers of the above type which will be compact in construction, thereby occupying a relatively 20 small space in the smoke box.

A further object is to provide a superheater of the above character which will be reliable and efficient in use and operation.

A further object is to provide a superheater having few parts which will be cheap 25 to manufacture and install and permit ready renewal or replacement of parts as may be necessary.

Other objects such as the overcoming of 30 certain objections to devices of this general character will be in part obvious and in part hereinafter pointed out.

The present invention accordingly consists in certain features of construction, combination of elements and arrangement of parts, the preferred form of which will be first described in connection with the accompanying drawings and then the invention particularly pointed out in the 40 appended claims.

In the accompanying drawings wherein the same part is designated by the same reference numeral and wherein is shown one of various possible embodiments of the present 45 invention: Figure 1 represents a longitudinal sectional view of such parts of a locomotive with a superheater as to enable one to understand the present invention; Fig. 2 is a front elevation of the same; Figs. 3 and 4 50 are longitudinal sectional views of the headers taken on lines 3-3 and 4-4, respectively, of Fig. 5; Figs. 5 and 6 are trans-

verse sectional views taken on lines 5-5 and 6-6, respectively, of Fig. 3, and Fig. 7 is a detail perspective view with certain parts 55 broken away for the sake of clearness.

Referring now to the drawings in detail and more particularly to Fig. 1, 10 designates a portion of the boiler shell, 11 the steam dome, 12 the stack, 13 the forward 60 tube sheet and 14 the tubes of the ordinary locomotive construction.

In the present construction an open ended dry pipe 15 leads from the upper part of the steam dome to a point just forward of 65 the tube sheet 13 and back of the smoke stack 12, where it enters a header 16 shown more clearly in Fig. 7, and formed in the present instance with three compartments or compactly arranged chambers. The first 70 compartment 17 communicates with a plurality of alternately arranged chambers 18, as shown in Fig. 3, each provided with outlet openings 20 communicating with superheater pipes 21. Each of these superheater pipes pass back and forth through a fire tube in the central part of the boiler and terminate in a chamber 22 provided with inlet openings 23. These chambers 22 alternate with the chambers 18, 80 as shown in Fig. 3, and all communicate with or form part of a second compartment or chamber 24 within the header 16. This compartment 24 in turn communicates at its central part through an opening 25 with a 85 third compartment or chamber 26 extending longitudinally within the header 16 and provided at each end with an outlet opening 27 and pipe 28 leading directly to the cylinders in a well-known manner.

An opening 25 is provided with a ring valve seat 30 with which a throttle valve 31, Fig. 1, is adapted to coact. This valve is of any desired type and in the form shown projects upwardly through the shell of 95 smoke-box 10', as shown in Fig. 1. A transverse operating shaft 33 extends to one side where it is provided with a crank 34 connected with a rod 35 leading back to the cab. It is believed to be unnecessary to go 100 into the details of this mechanism as it forms no part of the present invention, except in so far as it may broadly enter into certain combinations hereinafter set forth.

It is sufficient to state that as the rod 35 is moved in one direction the throttle is opened a corresponding amount and when moved in the opposite direction will approach or attain a closed position.

The upper part of the compartment 24 is provided with a branch pipe 40 which extends backwardly through the tube sheet 13 into the steam space of the boiler. The purpose of this pipe is in part to provide a constant circulation of steam within the superheater. Thus if the engine is stopped or drifting with the throttle in substantially closed position, the saturated steam will enter from the dome 11 through the dry pipe 15, thence through the superheater tubes to the second compartment 24 from which it will pass to the rear of the boiler through the pipe 40 to be either used or allowed to escape into the boiler to further heat the steam and water therein.

The operation of the present device is substantially as follows: The saturated steam enters the pipe 15 from the dome 11 and passes into the elongated compartment 17 within the header 16 from which it in turn enters the alternately disposed chambers 18 communicating therewith before passing through the outlet openings 20 into the superheater tubes 21 disposed within the fire tubes. The superheated steam is returned from these tubes to the alternately disposed chambers 22, Fig. 3, which communicate with the second or central compartment 24. The superheated steam then passes through the throttle valve 30, if open, into the third compartment 26 and thence to the cylinders through the pipes 28.

The compartments are preferably formed with single walls separating adjacent chambers not only for the cheapness of construction and installation, but for the purpose of compactly arranging them in the small space allowed for superheaters in the smoke-box.

It is to be noted that by locating the throttle between the superheater tubes and the cylinders, that superheated steam, when the throttle is closed, stands around the throttle and has a very short distance to travel to reach the cylinders when the throttle is opened which materially shortens the time elapsing between the opening of the throttle and the entry of steam into the cylinders.

It is thus seen that the present invention provides a simple and practical superheater particularly adaptable for boilers of the locomotive type which will be highly efficient in use and operation.

As many changes could be made in the above construction and many apparently widely different embodiments of my invention could be made, without departing from the scope thereof, it is intended that all matter contained in the above description or

shown in the accompanying drawings shall be interpreted as illustrative and not in a limiting sense.

I claim:

1. In combination with a boiler of locomotive type, of a superheater header comprising a relatively wide member extending transversely of the smoke box and comprising an inlet chamber connected with the steam space of the boiler, an outlet chamber connected with the cylinders, and an intervening chamber having its walls common to said first mentioned chambers having its main walls diagonally disposed with respect to said header, said intervening chamber being divided into sections and having pipes leading thereto after passing through the fire tubes of the boiler from said first chamber.

2. In combination with a boiler of locomotive type, of a superheater header comprising a sectional inlet chamber connected with the steam space of the boiler, an outlet chamber connected with the cylinders, and a sectional intervening chamber, said first and last chamber being connected one with another by superheater pipes passing through the fire tubes of the boiler, said chambers being integrally formed and of substantially the same size, the bottom wall of one chamber being the top wall of another and being diagonally disposed within said header.

3. In combination with a boiler of locomotive type, of a superheater header comprising an inlet, an outlet and an intervening chamber having common dividing walls, said dividing walls being diagonally disposed with respect to the superheater to provide chambers of substantially equal capacity, the inlet and intervening chamber being divided into alternate sections, each section of one being connected with an adjacent section of the other by looped superheating pipes leading through the fire tubes of the boiler, said outlet chamber having an inlet opening from the intervening chamber and an outlet opening for conducting the steam therefrom, a throttle valve in said opening positioned partly within and partly without the boiler, means for operating said throttle valve extending along the outside of the boiler, and a connection from the superheater to the boiler to deliver superheated steam back to the boiler whereby a circulation of steam may occur through the superheater at all times.

4. In combination with a boiler of locomotive type, of a superheater header comprising three substantially coextensive chambers including an inlet chamber to which steam is conducted from the steam space in the boiler, an outlet chamber for conducting superheated steam to the cylinders, and an intervening chamber having

diagonally disposed walls common with said first mentioned chamber, a valve opening between the intervening and outlet chamber having a loose valve seat, a valve coacting with said seat and projecting upwardly through the wall of the boiler, operating means for said valve extending along the outside of the boiler to the cab, said first chamber and intervening chamber being divided into alternate sections, and superheat-

ing tubes leading from one section through one of the fire tubes and then back to an adjacent section in the intervening chamber.

In testimony whereof I affix my signature in presence of two witnesses.

JOHN S. CHAMBERS.
